(57) **CLAIM**

The ornamental design for a garment liner, as shown and described.

DESCRIPTION

FIG. 1 is a front elevation of a garment liner, the rear elevation forming no part of the design;

FIG. 2 is a left side elevation of the garment liner of FIG. 1; FIG. 3 is a right side elevation of the garment liner of FIG. 1;

FIG. 4 is a top plan of the garment liner of FIG. 1; and, FIG. 5 is a bottom plan of the garment liner of FIG. 1. The broken lines shown in the drawings indicate structure and features which form no part of the claimed design.
